GAS HEATER

Benjamin C. Bartlebaugh, Wheeling, W. Va.

Application February 1, 1933. Serial No. 654,705

3 Claims. (Cl. 126—90)

The present invention is directed to improvements in gas heaters.

The invention has for one of its objects to provide a gas heater so constructed that all unburned gases escaping from the burner will be effectively mixed with incoming fresh air to eliminate any possibility of the unburned gas being discharged into the space to be heated.

Another object of the invention is to provide a heater of this character constructed in such a manner that fresh air is mixed with gas escaping from the burner and the mixture of unburned gas and the fresh air is compelled to pass to the flame jets of the burner in order that the unburned gas will be positively consumed, and will not be discharged into the room with the heated fresh air.

Still another and important object of the invention is the provision of a main air heating unit so constructed that the fresh air will not only be effectively heated before entering the room, but the air heated in the unit will as it is discharged therefrom greatly aid in drawing fresh air from the lower end of the heater as the heated air is discharged from the unit.

With these and other objects in view, this invention resides in the novel features of construction, formation, combination and arrangement of parts to be hereinafter more fully described, claimed and illustrated in the accompanying drawings, in which:—

Figure 1 is a front view of the heater.

Figure 2 is a rear view thereof.

Figure 3 is a sectional view on line 3—3 of Figure 1.

Figure 4 is a sectional view on line 4—4 of Figure 1.

Figure 5 is a perspective view of the main air heating unit.

Referring to the drawings, 1 designates a casing consisting of inner and outer laterally spaced end walls 2 and 3, respectively, which define air chambers 4, as clearly shown in Fig. 4 of the drawings. The front wall 5 is provided with slideable guard grilles 6 guided in the grooves 7 formed in opposite sides of the front opening 8.

The back plate 9 of the casing 1 is bolted to the rear of the heater and is provided with a row of horizontally disposed fresh air inlet openings 10. The lower edge of the plate 9 does not extend to the bottom of the heater so that an air admission slot 11 is provided.

The heater is supported by legs 12 of such length as to hold the bottom 12' thereof spaced from the floor in order that fresh air may pass

to the interior of the heater through the passage 13 defined by the fire wall 14 and partition 15, said wall and partition extending longitudinally of the combustion chamber 16.

The upper edge of the partition 15 terminates in an upwardly and forwardly inclined wall 17, which in turn terminates in a downwardly and forwardly inclined wall 18.

A top wall 19 is mounted above the wall 18 and has its rear edge bent downwardly to provide a rear wall 20, the lower edge of which bears against the inner surface of the plate 9 at a point slightly below the openings 10.

Upon reference to Fig. 3 it will be observed that the wall 15 and plate 9 define an air passage 21 which discharges into the air passage 22 defined by the wall 17 and 20, and that the fire wall 14 is supported by an angle bracket 23 clamped to the gas inlet pipe 24 and abuts the burner 25. Gas from a suitable source of supply is conducted to the burner 25 through the pipe 26, there being a valve 27 in said pipe to control the flow of gas. The valve 27 is controlled through the medium of a rod 28 extending along the bottom of the heater, the forward end thereof being provided with a handle 29 to facilitate operation of the rod, as is customary.

A top 30 is employed and forms in conjunction with the walls 19, 20 and the plate 9 an upper fresh air receiving chamber 31, air thereto being admitted through the inlet openings 10 and the openings 32 formed in the end walls 2. Vertically disposed air conducting channel members 33 are mounted in the air chambers 4 so that air can pass freely through the members from the lowermost openings 32 to the uppermost ones.

The side flanges 34 and the front flange 35 of the top 30 are provided with air outlet openings 36.

A baffle plate 37 is suspended below the wall 18 by brackets 38, and has its inner edge aligned with and vertically spaced from the upper edge of the fire wall 14, there being a passage 39 between said plate and wall.

Fresh air entering the passage 13 from the opening 40 and from the bottom of the heater 100 will be forced by the heat from the burner into the flame of the burner in a manner to be hereinafter described.

A main heating unit 41 is employed and consists of a plurality of flues 42 secured in spaced relation by a metal sheet 43 riveted to the respective flues.

The unit 41 is mounted between the top wall 19 and the wall 18, as clearly shown in Fig. 3, and is supported in such position by a longitudinally

extending plate 43, the longitudinal edges of which are suitably secured respectively, to the flues 42 and wall 18. The inner ends of the flues 42 rest upon the wall 18 and adjacent the rear end thereof and have direct communication with the air passage 22.

The bracket 23 is provided with a plurality of perforations 44 in order that air and unburned gas from the passage 13 may enter the combustion chamber 16 and be subjected to the flame of the burner 25.

When gas from the burner 25 is ignited the hot unburned gases will ascend and be directed rearwardly by the baffle plate 37 and wall 18, and thence rapidly downwardly by the wall 17 behind the fire wall 14 and into the passage 13. The hot non-consumed gases will rapidly commingle with the air in the passage 13 and this mixture of air and gases is then blown through the perforations 44 with considerable velocity, and this mixture is directed under pressure into the ascending flame of the burner, thereby positively burning the unburned gases to eliminate the discharge of unburned gases into a room. As long as the burner 25 is in operation this cycle takes place and the discharge of obnoxious odors and dangerous gases into a room is positively prevented.

Obviously heat in the combustion chamber 16 will heat the baffle plate 37, wall 18 and plate 43 and is transmitted to the flues 42, which are located at the "hottest point" of the heater. After the flues have become well heated, and due to their location, the air heated therein rapidly discharges, and due to this rapid discharge of heated air a rather strong suction is created in the passages 22 and 21 which will draw fresh air from the bottom of the heater into the flues.

Heat from the flues 42 will heat the walls 19 and 20 to a considerable extent, and consequently fresh air entering the chamber 31 through openings 10 and 32 will be heated and discharged through the openings 36 of the top 30.

What is claimed is:—

1. A gas heater comprising a casing including a front having an opening therein, and a back plate, a wall in the casing spaced from the top wall thereof and having its rear edge abutting the back plate, said casing having a combustion chamber therein including a top wall and a partition, the top wall and partition forming in

conjunction with the first named wall and the back plate a fresh air passage, a main heating unit mounted between the first named wall and top wall of the combustion chamber, said unit consisting of a plurality of laterally spaced flues having their rear ends communicating with said passage and their front ends discharging through the opening of the front of the casing, the rear ends of said flues resting on the top wall of the combustion chamber, and means connecting the forward ends of the flues to the top wall of the combustion chamber.

2. A gas heater comprising a casing including a front having an opening therein, and a back plate, a wall in the casing spaced from the top wall thereof and having its rear edge abutting the back plate, said casing having a combustion chamber therein including a top wall and a partition, the top wall and partition forming in conjunction with the first named wall and the back plate a fresh air passage, a main heating unit mounted between the first named wall and top wall of the combustion chamber, said unit consisting of a plurality of laterally spaced flues having their rear ends communicating with said passage and their front ends discharging through the opening of the front of the casing, the rear ends of said flues resting on the top wall of the combustion chamber, and a plate having its longitudinal edges fixed, respectively, to the flues and top wall of the combustion chamber.

3. A gas heater comprising a casing including a front having an opening therein, and a back plate, a wall in the casing spaced from the top wall thereof and having its rear edge abutting the back plate, said casing having a combustion chamber therein including a top wall and a partition, the top wall and partition forming in conjunction with the first named wall and the back plate a fresh air passage, a main heating unit mounted between the first named wall and top wall of the combustion chamber, said unit comprising a flue having its rear end communicating with said passage and its forward end discharging through the opening of the front of the casing, the rear end of said flue resting on the top wall of the combustion chamber, and means connecting the forward end of the unit to the top wall of the combustion chamber.
